US0D1114201S

(12) **United States Design Patent** (10) **Patent No.:** **US D1,114,201 S**
(45) **Date of Patent:** **** Feb. 17, 2026**

(54) **HOSE CONNECTOR**

(71) Applicants: **KUNSHAN AMPHENOL ZHENGRI ELECTRONICS CO., LTD.**, Kunshan (CN); **AMPHENOL LTW TECHNOLOGY CO., LTD.**, New Taipei (TW)

(72) Inventors: **Jhih-Ping Lee**, New Taipei (TW); **Kun-Te Ko**, New Taipei (TW)

(73) Assignees: **KUNSHAN AMPHENOL ZHENGRI ELECTRONICS CO., LTD.**, Kunshan (CN); **AMPHENOL LTW TECHNOLOGY CO., LTD.**, New Taipei (TW)

(**) Term: **15 Years**

(21) Appl. No.: **29/992,763**

(22) Filed: **Mar. 11, 2025**

(51) LOC (15) Cl. **23-01**

(52) U.S. Cl.

USPC **D23/262**

(57) **CLAIM**

The ornamental design for a hose connector as shown and described.

DESCRIPTION

FIG. 1 is a perspective view of a hose connector showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is a second perspective view showing the hose connector;

FIG. 9 is a perspective view showing the hose connector connected with a host element.

The broken lines shown in the figures are for the purpose of illustrating portions of the hose connector and environmental structure in FIG. 9 that form no part of the claimed design.

1 Claim, 8 Drawing Sheets
